UNITED STATES PATENT OFFICE

2,096,192

LOUDSPEAKER UNIT

Aston L. Moore, South Bend, Ind.

Application July 1, 1937, Serial No. 151,409

8 Claims. (Cl. 181—31)

This invention relates to loud speaker units and primarily to such units for use in public address systems where it is desired to broadcast the words of a speaker in all directions from the loud speaker, although it is of particular value in certain types of radio reproduction work.

The objects of the invention are:

First, to produce a new and improved loud speaker unit.

Second, to produce such a unit which may be hung in a place exposed to the elements without injury to the unit.

Third, to provide such a unit which is of simple, inexpensive construction which may be hung in any desired position and from which the sound is directed to all points of the compass and is further directed so as to be audible to a great number of persons located near the speaker.

Fourth, to provide such a unit in which the sound emanating from the diaphragm is spread in all directions by a simple baffle means.

Fifth, to produce such a speaker which may be used in radio reproduction work and in which the sounds reproduced are spread to all parts of a room in which the speaker is employed.

Other objects and advantages pertaining to details and economies of construction and operation will appear in the description to follow. Preferred embodiments of my invention are illustrated in the accompanying drawings, in which:

Fig. 1 is a side elevational view of a loud speaker unit embodying my invention and suitable for public address work.

Fig. 2 is a view of the same speaker partly in section showing the arrangement of the parts therein.

Fig. 3 is a bottom plan view of the speaker unit shown in Fig. 1.

Fig. 4 is a cross sectional view taken on line 4—4 of Fig. 2.

Fig. 5 is a view of a different form of loud speaker embodying my invention shown partly in section.

Fig. 6 is a view of the speaker shown in Fig. 5 supported in a manner different from that shown in Fig. 5.

In Figs. 1—4 of the drawings, I show a form of my loud speaker unit particularly adapted for outdoor public address systems. A baffle 1 having a substantially central aperture 2 is provided. The baffle 1 may be made of pressed wood or any other suitable material and is preferably round in contour. A dome-shaped cover member 3 is provided and this is fastened to the baffle above the aperture 2 and covering said aperture by bolts 4

passing through spacing lugs 5 which space the bottom of the cover member 3 from the top of the baffle. An annular flange 6 extends upwardly from the baffle inside of the cover member 3 and to a height greater than the opening between the cover member and the baffle. The object of this arrangement is to protect the loud speaker unit 7, which is mounted inside the baffle, from the elements. A hook 8 is provided at the top of the cover member 3 for supporting the speaker unit 10 from any suitable hanger.

The loud speaker unit which is not shown in detail is a standard loud speaker unit having a conical diaphragm 9. This diaphragm is disposed with its concave side directed toward the opening 2 in the baffle and the edge of the unit 7 is fastened to the baffle by suitable screws 10 so that the baffle will prevent the cancellation of sound through the vibration of the diaphragm and the sound waves sent out from the rear thereof.

Directly below the conical diaphragm is a conical deflector 11 which is substantially the same shape as the conical diaphragm. This deflector 11 is located on the axis of the conical diaphragm 9 and has its apex directed toward said diaphragm. The deflector 11 is disposed in spaced relationship to the diaphragm 9 and has at its edge a baffle 12 which is joined thereto. A supporting frame consisting of the radial supporting members 13 which are fastened to the radial members 14 by screws 15 are provided. The radial members 14 lie on top of the baffle 1 and the screws extend through the baffle and into the radial supporting members 13. The members 13 hold the baffle 12 parallel with the baffle 1 and in spaced relationship thereto. It will be noted that the baffle 12 is smaller than the baffle 1 which permits the sound waves to be directed somewhat downwardly by the baffle 1 as they leave the loud speaker unit. The baffle 12 is fastened by the bolts 16 to the radial supporting members 13 and a screw threaded socket 17 is provided at the junction of the members 13 to receive any suitable screw threaded support which it may be desired to insert therein.

A perforated screen 24 is provided extending between the baffles 1 and 12 to exclude insects and other objectionable matter.

In employing the loud speaker unit, the sound waves directed downwardly by the loud speaker unit are deflected by the conical deflector 11 and pass between the baffles 1 and 12 and are directed to all points of the compass. The larger baffle 1 tends to direct the sound waves more or less downwardly as they leave the unit so that a broad-

cast from the speaker to a crowd will more effectively reach all members of the crowd.

In Figs. 5 and 6 I show a slightly modified form of my device for use in public address systems. The baffle 101 is provided with an aperture 102 and a cover member 103 which is, in this instance, the shape of a half sphere. The supporting member 108 is provided on the cover 103 and a supporting member 208 is provided for supporting the speaker in the position shown in Fig. 6. The cover member 103 is provided with a plurality of apertures 18 to relieve air pressure created through the operation of the loud speaker unit 107 which has the conical diaphragm 109 disposed at the aperture 102 and connected thereto. At the bottom of the baffle 101 and disposed over the aperture 102 therein is a second cover member 10. This cover member is half spherical in the construction shown. It is provided with a plurality of apertures 20 whose total area is greater than the area of the diaphragm 109 of the loud speaker unit. A baffle 111 is supported in the member 10 and is disposed with reference to the conical speaker diaphragm 109 just as is the conical deflector 11 with reference to the conical diaphragm 9 of the loud speaker unit in the structures shown in Figs. 1-4, that is, on the same axis spaced therefrom and with its apex directed toward said diaphragm 109. The baffle member 101 is supported by the cover members 103 and 10. These are provided with flanges 21 and 22 which are joined together by bolts 23.

It will be appreciated that when this loud speaker is in use, the deflector 111 deflects the sound waves created by the diaphragm 109 so that they are spread out to all points of the compass and are directed more or less downwardly by the baffle 101 to reach the larger portion of the audience.

40 It will be appreciated that although loud speakers of the type here described are suitable for public address systems, they are also very well suited for reproduction of radio broadcasts and that when such a speaker is in use reproducing 45 radio broadcasts the broadcast is directed to all parts of the room in which the speaker is used.

I have shown and described my preferred constructions and wish to claim the same broadly and specifically as pointed out in the following 50 claims.

Having thus described my invention, what I claim as new and desire to secure by Letters Patent is:

1. The combination of a baffle having a substantially central aperture, a cover member disposed above and covering said aperture and having its edge spaced from said baffle, means fastening said cover member and baffle together, a loud speaker disposed in said cover member and having a concave conical diaphragm disposed at and directed toward said opening in said baffle, means connecting the edge of said speaker unit with said baffle, a flange extending upwardly from said baffle around said speaker unit and spaced inwardly from said cover member, a conical deflector of substantially the same shape as the conical diaphragm disposed on the same axis as and spaced from and having its apex directed toward said diaphragm, a second baffle extending from the edge of said deflector and parallel with and spaced from said first named baffle, means for supporting said baffle and said deflector in position, and supporting means fastened to said cover member.

75 2. The combination of a baffle having a sub-

stantially central aperture, a cover member disposed above and covering said aperture, a loud speaker unit disposed in said cover member having a concave conical diaphragm disposed at and directed toward said opening in said baffle, means connecting the edge of said speaker unit with said baffle, a conical deflector of substantially the same shape as the conical diaphragm disposed on the same axis as and spaced from and having its apex directed toward said diaphragm, a second baffle extending from the edge of said deflector and parallel with and spaced from said first named baffle, and means for supporting said baffle and said deflector in position.

3. The combination of a baffle having a substantially central aperture, a loud speaker unit having a concave conical diaphragm disposed at and directed toward said opening in said baffle, means connecting the edge of said speaker unit with said baffle, a conical deflector of substantially the same shape as the conical diaphragm disposed on the same axis as and spaced from and having its apex directed toward said diaphragm, a second baffle extending from the edge of said deflector and parallel with and spaced from said first named baffle, and means for supporting said baffle and said deflector in position.

4. The combination of a baffle having a substantially central aperture, a loud speaker unit having a concave conical diaphragm disposed at and directed toward said opening in said baffle, means connecting the edge of said speaker unit with said baffle, a conical deflector of substantially the same shape as the conical diaphragm disposed on the same axis as and spaced from and having its apex directed toward said diaphragm, and means for supporting said deflector in position.

5. The combination of a baffle having a substantially central aperture, a cover member disposed above and covering said aperture, means fastening said cover member and baffle together, a loud speaker unit disposed in said cover member and having a concave conical diaphragm disposed at and directed toward said opening in said baffle, means connecting the edge of said speaker unit with said baffle, said cover member being apertured for the relief of air pressure therein, a second cover member disposed below and covering said aperture and fastened to said baffle, a 40 conical deflector supported in said second cover member and on the same axis as and substantially the same shape as said conical diaphragm, said deflector being spaced from said diaphragm and having its apex directed toward said diaphragm, a plurality of apertures in said second cover member and having a total area at least as great as the area of said diaphragm, and means on said first mentioned cover member by which it may be hung.

6. The combination of a baffle having a substantially central aperture, a cover member disposed above and covering said aperture, means fastening said cover member and baffle together, a loud speaker unit disposed in said cover member and having a concave conical diaphragm disposed at and directed toward said opening in said baffle, means connecting the edge of said speaker unit with said baffle, a second cover member disposed below and covering said aperture and fastened to said baffle, a conical deflector supported in said second cover member and on the same axis as and substantially the same shape as said conical diaphragm, said deflector being spaced from said diaphragm and having its apex directed toward 75

said diaphragm, a plurality of apertures in said second cover member and having a total area at least as great as the area of said diaphragm, and means on said first mentioned cover member by which it may be hung.

7. The combination of a baffle having a substantially central aperture, a cover member disposed above and covering said aperture, means fastening said cover member and baffle together, 10 a loud speaker unit disposed in said cover member and having a concave conical diaphragm disposed at and directed toward said opening in said baffle, means connecting the edge of said speaker unit with said baffle, a second cover member disposed below and covering said aperture and fastened to said baffle, a conical deflector supported 15 in said second cover member and on the same axis as and substantially the same shape as said conical diaphragm, said deflector being spaced from said diaphragm and having its apex directed toward said diaphragm, and a plurality of apertures 20 from said diaphragm and having its apex directed toward said diaphragm, a plurality of

apertures in said second cover member, and means on said first mentioned cover member by which it may be hung.

8. The combination of a baffle having a substantially central aperture, a cover member disposed above and covering said aperture, means fastening said cover member and baffle together, a loud speaker unit disposed in said cover member and having a concave conical diaphragm disposed at and directed toward said opening in said baffle, means connecting the edge of said speaker unit with said baffle, a second cover member disposed below and covering said aperture and fastened to said baffle, a conical deflector supported 10 in said second cover member and on the same axis as and substantially the same shape as said conical diaphragm, said deflector being spaced from said diaphragm and having its apex directed toward said diaphragm, and a plurality of apertures 15 in said second cover member. 20
